UNITED STATES PATENT OFFICE

155,457

DESIGN FOR A RUBBER GLOVE

Albert E. Sidnell, Akron, Ohio

Application August 17, 1948, Serial No. 148,141

Term of patent 14 years

(Cl. D3—11)

To all whom it may concern:

Be it known that I, Albert E. Sidnell, a citizen of the United States, residing at Akron, in the county of Summit and State of Ohio, have invented a new, original, and ornamental Design for Rubber Gloves, of which the following is a specification, reference being had to the accompanying drawings, which form a part thereof.

Fig. 1 is a front view of a rubber glove showing my new design;

Fig. 2 is a side view thereof shown partially broken away;

Fig. 3 is a rear view thereof;

Fig. 4 shows a fragmentary portion of the front of the third finger of the glove, i. e., the finger next to the little finger, enlarged four times;

Fig. 5 is a section on the line 5—5 of Fig. 4; and Fig. 6 is a section on the line 6—6 of Fig. 4.

I claim:

The ornamental design for a rubber glove, as shown and described.

ALBERT E. SIDNELL.
